UNITED STATES PATENT OFFICE.

GEORGE H. EARLE, OF VALPARAISO, INDIANA.

AUTOMOBILE-HEATER.

1,308,486.

Specification of Letters Patent.

Patented July 1, 1919.

Application filed December 18, 1915. Serial No. 67,586.

To all whom it may concern:

Be it known that I, GEORGE H. EARLE, citizen of the United States, residing at Valparaiso, in the county of Porter and State of Indiana, have invented certain new and useful Improvements in Automobile-Heaters, of which the following is a specification.

My invention relates to improvements in automobile heaters and it consists of the special features pointed out in the annexed claims.

The purpose of my invention is to provide a simple and effective heater for automobiles, etc., which will utilize as much of the exhaust gases as are necessary to warm the space in which the heater is placed; to provide a heat radiating surface; to provide a storage of heat that will continue to radiate for a long period after the exhaust is shut off through a stoppage of the engine; that can easily be installed on existing cars; that is durable, inexpensive and free from complicated parts; that may combine within itself the functions of a muffler as well as a heater; that may be placed directly in the space to be heated or beneath a floor register; and that provides for the circulation of air to increase the radiation.

With these and other ends in view I illustrate in the accompanying drawings such instances of adaptation as will disclose the broad fundamental features without limiting myself to the specific details shown.

Figure 1— is a diagrammatic elevation showing a heater applied to a number of many possible locations.

Fig. 2— is an elevation partly in section of an instance adaptation, attached to the exhaust pipe.

Fig. 3— is an end elevation of Fig. 2.

Fig. 4— is a detail sectional elevation showing a center rod or tube passing through the heater.

Fig. 5— shows a combined heater and muffler.

Fig. 6— is a face and edge elevation of a simplified form of valve.

Fig. 7— is an elevation of the valve stem and finger piece for operating same.

In carrying out an adaptation of my invention I may attach the heater 4 to any part of the exhaust pipe 2 leading from the manifold 1 of the engine. The approximate rela-

tion of an ordinary muffler is shown at 3 55 when heaters 4 are installed in connection with the same.

The radiating walls 5 may simulate a helix or screw shape in which the inner channel 6 makes a tortuous passage from a 60 tangential intake 9 to a similar outlet 15. In one form the center is cored out of a casting so that between adjacent walls, as at 7 a contracted opening is formed for each convolution of the radiating fins 5. This 65 opening or passage passes through the heads at both ends where suitable plugs 8 may be inserted. If desired I may introduce a short rod 20 as shown in Fig. 4 to confine the incoming gases to a few turns near the inlet 70 end before allowing them to commingle among openings 7 and spaces 6 beyond the end of rod 20. Should it be desired I may place a solid rod or tube of any desired diameter through the entire length of the 75 heater casting. If such a tube is used instead of plugs 8 its ends may be left open to induce a movement of air through it if the heater is slightly inclined or placed vertically or heated more at one end than the 80 other and thus promote a general circulation of air within the compartment.

A disk valve 10 secured to stem 11, through handle piece 12 enables the user to turn the heat on or off manually as required. This 85 disk may be stamped with opposing semi-circular grooves on alternate portions as shown in Fig. 6 so as to pass over the valve stem 11. The central portion may be flattened at 38 to coöperate with the flattened part 36 of the valve stem so that the stem can simply be driven into the grooves of disk 10 while it is in the inlet passage, so as to hold the disk against turning on the stem without the use of screws, pins, etc. 95 The handle part 12 may be stamped out as shown in Fig. 7 with an "arch" formed to enter slot 37. A groove 39 on the stem 11 forms a means for handle 12 in place on the stem when the projections on each side 100 of arch 40 are pressed into the groove, thus holding the parts assembled. It is of course immaterial as to whether these specific details are used or not as many equivalents will suggest themselves during the course of 105 manufacture, etc.

The adaptation shown in Figs. 2 and 3 may be placed directly on the car floor 13

at one or more places. It is secured to the floor by screws or other means passing through flanges 14. Projections 16 serve as inlets and outlets. In the latter case, if required I may contract the outlet at 17 so as to further silence the heater or this may also be accomplished by increasing the effective length of passage 6, or the closing of openings 7, or the forming of the convolutions 10 at a greater pitch as they approach the outlet. The projections 16 pass through suitable holes made in floor 13, the outlet 17 simply opening into the air. Connector 18 suitably supported leads from the exhaust pipe when heaters are connected during the process of manufacture, or when installed on existing cars they may be clamped by any suitable means. One way of accomplishing this is to use a flat plate 19, perforate it for connector 18 whose entering end may be rolled over as needed and then bend the plate around the exhaust pipe 2, clamping the two ends together, or it may be secured in any other desired manner, so that both 25 joints are gas tight.

The heater and muffler may be combined as a unit by locating the device beneath the car floor and placing a register 34 above an opening formed in the floor, the usual 30 form of a shut-off 35 being used to control the heat. For winter driving a protective casing 41 may be used to retain the heat and for summer purposes it may be removed and the damper 35 kept closed. To increase the 35 muffling effect more than one casting 4 may be placed within the casing 41. It is immaterial, in a general sense what angular lead is given the convolutions 5 as this pitch may be changed to suit various practical necessities 40 and if desired a single element 4 may comprise different pitches in one structure 5.

For inclosed cars it may be found desirable to automatically control the heat. To accomplish this well known thermostats may 45 be used, as such a control is not claimed herein it is not shown.

What I claim is,

1. A heat radiator, comprising an inlet and outlet, an interconnected circulatory 50 passage leading from one to the other formed of large and small diameter convolutions, having suitable walls which connect the convolutions to produce a large radiating surface that is continuously connected with an opening inside of the smaller

diameter convolutions to which the inlet and outlet are connected.

2. A heat radiator, comprising a tortuous passage formed as convolutions traversing around an open center included in said passage, suitable connections therefrom to an inlet and an outlet, and means within the inlet to control admission thereto. 60

3. A heat radiator, comprising a screw shaped member having an open center, a 65 screw formed passage surrounding the same and continuously connected therewith, suitable inlet and outlet openings thereto, and means for controlling passage through the member. 70

4. A combined heat radiator and muffler, comprising a continuous tortuous passage, an opening through its center, distinctive from but continuously connected to said passage, and a suitable inlet to and outlet from 75 the opening and the passage.

5. A heat radiator, comprising a series of screw shaped units comprising one revolution to each connected together side by side 80 having an open passage through the center 80 thereof and integrally formed throughout with inlet and outlet heads at the ends of the units.

6. A combined heat radiator and pressure reducer, comprising a tortuously advancing 85 angular shaped division wall of approximate screw-shaped formation forming a tortuous passage therein, and suitable openings at the extremes of the passage serving as inlet and outlet therefor. 90

7. A heat radiator comprising a spirally disposed passage whose sides are formed at an angle to each other and to the axis of the radiator whereby a maximum radiating surface is secured with a minimum heat stream, and means for controlling flow therethrough. 95

8. A heat radiator, comprising a spirally disposed partitioning wall inclosing a chamber therethrough, a spiral groove external of the chamber constituting a radiator, a 100 suitable support for the wall, and an inlet and outlet to said chamber formed within the supports.

In testimony whereof I affix my signature in presence of two witnesses.

GEORGE H. EARLE.
